UNITED STATES PATENT OFFICE.

WILLIAM F. BAYER, OF BUFFALO, NEW YORK.

AUTOMATIC MUSICAL INSTRUMENT.

1,107,571.

Specification of Letters Patent.

Patented Aug. 18, 1914.

Application filed January 30, 1911. Serial No. 605,438.

To all whom it may concern:

Be it known that I, WILLIAM F. BAYER, a citizen of the United States, residing at Buffalo, in the county of Erie and State of New York, have invented new and useful 5 Improvements in Automatic Musical Instruments, of which the following is a specification.

This invention relates to player-pianos, 10 piano players and similar musical instruments, and more particularly to instruments in which the main bellows and associated parts are readily removable from the piano-case to facilitate the making of repairs and 15 afford convenient access to the strings. In such instruments, as hitherto constructed, it is necessary in order to remove the main bellows, to disturb or remove the bearings of the rock shafts which carry the usual 20 tempo, expression and rewind keys or levers whereby the valves of the air motor and the expression or accent devices are controlled.

The object of my invention is to so construct these controlling devices that the shaft 25 bearings are allowed to remain intact and undisturbed when the bellows is removed, thus not only facilitating this operation but also maintaining the adjustment of the parts.

30 In the accompanying drawings consisting of 4 sheets: Figure 1 is a fragmentary front elevation of a player-piano embodying the invention, with the lower front panel of the case removed. Fig. 2 is a sectional rear 35 view of the lower portion of the instrument. Fig. 3 is a top plan view of the main bellows and associated parts. Figs. 4 and 5 are horizontal sections on the correspondingly numbered lines in Fig. 1. Fig. 6 is a 40 fragmentary front view of the air reservoir of the main bellows, omitting the motor, governor and expression devices to show the ports in the front wall thereof. Figs. 7, 8 and 9 are vertical sections on the correspondingly-numbered lines in Fig. 4. Fig. 10 is a 45 sectional front elevation, on an enlarged scale, of part of the valve-operating mechanism. Fig. 11 is a top plan view of the main bellows and the divided valve-operating 50 shafts. Fig. 12 is a vertical section on line 12-12, Fig. 11. Fig. 13 is a similar section on line 13-13, Fig. 12. Fig. 14 is a transverse section on line 14-14, Fig. 12. Fig. 15 is an enlarged longitudinal section 55 of one of the clutches.

Similar letters of reference indicate cor-

responding parts throughout the several views.

A indicates the pumps of the main suction bellows of the instrument which are 60 operated by the usual folding pedals A¹.

B indicates the feeders and C the customary air reservoir. D, D¹ indicate independent air conduits or channels arranged on the upper rear side of said reservoir at 65 or near opposite ends thereof, and d, d¹ are tubes connecting said channels respectively with opposite ends of the usual main exhaust chamber of the wind chest E. The channel D, which is preferably located at 70 the left hand end of the reservoir C, is connected with the latter through an air governor or pressure regulator which maintains a uniform air tension or suction in the wind chest for comparatively soft playing 75 and includes an accent port and valve by which the adjacent end of the wind chest may be placed in direct communication with the reservoir C for loud or accented playing. This governor and accent device may 80 be of any suitable construction, but is preferably like that shown and described in Letters Patent of the United States No. 961,335, granted to me June 14, 1910. As best shown in Figs. 4, 5 and 7, F indicates 85 the inlet chamber of this governor which communicates with the air channel D by an accent port f; G its outlet chamber which connects with the air reservoir C by a port g; h the accent port in the partition between the chambers F and G; h¹ the sliding accent valve controlling said port, and I the governor bellows or pneumatic communicating with the outlet chamber G by a port i and with the air channel D by a port 95 i¹ independent of the accent port f.

In the operation of the instrument, the movable wall of the governor bellows approaches the face of the block i² containing the port i more or less closely, thus equalizing the air tension in the wind chest, as more fully described in the above-mentioned Letters Patent. To accentuate any desired notes or passages of the music, the accent valve h is opened more or less, thus placing 100 the air channel D and the corresponding end of the wind chest in direct communication with the air reservoir C and causing the instrument to play with corresponding loudness.

j indicates the cut off valve applied to the port g of the air reservoir, this valve being 110

normally open. During the rewinding of the customary music sheet, said valve is closed to cut off the bass section of the wind chest from the main bellows. In order to 5 provide a short and direct course for the wind between the opposite or treble end of the wind chest and the air reservoir C for accentuation and loud playing, I employ the channel D¹ in combination with an accent valve k corresponding to the accent valve h¹, and a cut-off valve l corresponding to the cut-off valve j. The accent valve k is arranged in a horizontal case k¹ applied to the rear side of the channel D¹ and to an 10 auxiliary or connecting chamber k² arranged on the rear side of the front wall of the air reservoir C beside the channel D¹, as seen in Figs. 4 and 8. Ports k³, k⁴ connect the chamber k¹ with the channels D¹ and k², respectively, the accent valve k being applied 15 to said port k⁴. The cut off valve l is arranged in a case L applied to the front wall of the air reservoir C and controls a corresponding port l² in said wall. Above the port l² is another valveless port l³ which 20 constantly connects the chamber k² with the cut-off case or chamber L, as shown in Fig. 8.

When the cut-off valve l and the corresponding accent valve k are opened, as 25 shown in Figs. 4 and 5, the air is exhausted from the treble end of the wind chest through the tube d¹, channel D¹, port k³, valve-case k¹, accent-port k⁴, chamber k², and ports l³, l². In the preferred construction shown in the drawings, the two accent valves h¹ and k are connected to move in unison, so that they may be opened and closed simultaneously, and the two cut-off 30 valves j and l are likewise coupled. Accordingly, as shown in Figs. 3 and 4, the stems of said accent valves are connected by links m, m¹ with arms m², m³, secured to a horizontal rock shaft m⁴ arranged under the key 35 table and having an operating key or finger m⁵ arranged at the front of the instrument. A spring m⁶ serves to return the accent finger m⁵ and connected parts to their initial position. As best shown in Fig. 10, 40 this spring is interposed between a fixed bracket m⁷ and a collar m⁸ secured to a rod m⁹ guided in said bracket and attached to an arm of said shaft.

The stems of the two cut-off valves j and 45 l are operated from a horizontal rewind shaft n through the medium of an upright rock shaft n¹ having an arm n² with which said stems are connected by links n³, n⁴. This upright shaft is connected with the rewind shaft n by arms o, o¹ and a link o², Fig. 11. The rewind shaft is arranged under the key table parallel with the shaft m⁴ and provided with the usual operating key or finger n⁵. Connected with the 50 upright shaft n¹ by an arm p and a link p¹, is

the stem p² of the usual rewind valve of the governor P which controls the air motor of the music sheet, whereby the rewind valve is opened simultaneously with the closing of the cut-off valves j and l.

Attached to an arm p³ of the rewind shaft is a rod or link p⁴ which at its opposite end is connected to a connection p⁵ by which is shifted the usual rewind gearing of the music sheet which gearing is not shown in the drawings and forms no part of this invention.

It will be understood from the foregoing, that for accent purposes or loud playing, each end or half of the wind chest has its own independent and direct connection with the main suction bellows, the one through the accent port h of the pressure regulator or governor and the other through the ported chambers D¹, k¹, k² and L as herein-before described; also that the two end-portions of the wind chest have separate cut-off valves j and l. By providing such direct accent passages between both ends of the wind chest and the main bellows, instead of a single connection at one end thereof, the travel of the wind to both the treble and bass sections of the pneumatic action is correspondingly shortened and an ample quantity is supplied to each, thus rendering all parts of the action promptly responsive to the opening of the accent valves, and permitting an almost instantaneous change from soft to loud playing or vice versa, if desired.

q indicates the tempo-key or finger mounted on a horizontal rock shaft q¹ similar to the shafts m⁴ and n and preferably located between the latter, as shown. The stem q² of the usual tempo regulating valve (not shown) is connected by a link q³ with a rock arm q⁴ on the shaft q¹.

q⁵ is the rod or connection leading from an arm q⁶ on the tempo-shaft q¹ to the customary tempo-indicator.

r indicates the usual rock shaft by which the customary damper-levers are operated and which is journaled on the underside of the key table; and r¹ is the connection leading from an arm r² on said shaft to the usual operating element of said levers.

The entire bellows structure, including the air reservoir, pumps, feeders and other parts mounted thereon, is removably secured in the piano case. For this purpose said structure is fitted between a pair of uprights or posts s, suitably secured to the floor of the case and the underside of the key table, being held in position by removable pins s¹ passing through the sides of the posts and 120 entering holes in the side walls of the bellows, as shown in Figs. 1 and 2, or by other suitable means.

To permit the removal of the bellows-structure without disturbing the bearings of 125

the several shafts m^4 , q^1 and n , the latter are divided into separable front and rear sections, as shown in Fig. 11, and their rear sections are mounted in a horizontal supporting frame T secured to the upper front portion of the air reservoir or other rigid part of the bellows structure while their front sections are supported in bearings u secured to the underside of the key-table, which is shown by dotted lines in Fig. 11. The supporting frame T may be of any suitable construction, that shown in the drawings comprising spaced longitudinal bars t and transverse tie rods t^1 . This frame also carries the upright rock shaft n^1 .

The front and rear sections of the horizontal shafts m^4 , q^1 and n are normally connected together by clutches or couplings of any suitable construction. In the preferred construction shown in the drawings, the rear section of each of said shafts has in its front end a mortise v which receives a tenon or flattened portion v^1 at the rear end of a clutch-collar v^2 slidable on the front shaft section and normally clamped thereon by a set screw v^3 . This collar preferably has a sleeve or tubular extension v^4 which overlaps the rear section of the shaft and serves to retain the coupled sections in alinement. This construction, while compelling the two parts of the shafts to turn together, permits their disconnection by a longitudinal movement of one part on the other.

To remove the bellows-structure, the pins s are withdrawn, the tubes d , d^1 are detached from the side walls of the air reservoir C , the collars v^2 are released and slid forwardly, and the connecting rods p^4 , q^5 and r^1 extending normally across the bellows-structure are detached from the respective shaft-arms, whereupon the latter can be withdrawn from the piano-case. After replacing the bellows, the sections of the several shafts are re-coupled by sliding the collars v^2 rearwardly, and the removed and detached parts above mentioned are replaced.

By mounting said valve-operating shafts partly on the main bellows and partly on the piano-case or key-table, the bellows can be readily installed and removed, when required, without the necessity of removing the shafts or parts of their bearings from the underside of the key-table, retaining the parts in proper adjustment as well as facil-

tating the removal of the bellows and effecting an important saving in time.

I claim as my invention:

1. In an instrument of the character described, the combination of an inclosing case having an overhanging part, a main bellows-structure removably arranged in the case below said overhanging part, an accessory coöperating with said bellows, a valve controlling said accessory, an operating shaft for said valve composed of a rear section carried by said bellows-structure and a front section supported on the underside of said overhanging part in alinement with said rear section, and means for separably connecting said shaft-sections. 70

2. In an instrument of the character described, the combination of an inclosing case having an overhanging part, a main bellows-structure removably arranged in the case below said overhanging part, a plurality 75 of accessories coöperating with the bellows-structure, valves controlling said accessories, a supporting frame secured to and projecting forwardly from the bellows-structure adjacent to said overhanging part, and a plurality of actuating shafts for said valves, each composed of a rear section journaled in said frame and a front section separably connected with the rear section and journaled on the underside of said overhanging 85 part.

3. In an instrument of the character described, the combination of an inclosing case having a key-table, a main bellows-structure removably arranged therein below said table, 90 a plurality of accessories coöperating with the bellows-structure, valves controlling said accessories, a supporting frame secured to the front of the bellows-structure adjacent to the underside of the key-table, a plurality 95 of actuating shafts for said valves, each comprising separable front and rear sections, the rear sections of the several shafts being carried by said frame and their front sections by the key-table, and coupling 100 means for the sections of said shafts.

Witness my hand this 21st day of January, 1911.

WILLIAM F. BAYER.
